CAN TOP LABEL

George I. Chatfield, Winchester, Mass., assignor
to Lever Brothers Company, a corporation of
Maine

Application February 7, 1935, Serial No. 5,355

12 Claims. (Cl. 40—7)

This invention relates to can top labels and particularly to labels adapted to be applied to cans or other containers having an opening tool removably secured to the top or other cover thereof.

Many products are placed upon the market in cans each having a top or other cover to which is removably secured an opening tool such as the familiar key type that is applied to a sealing strip for tearing the latter off to open the can. Among the products merchandised in containers of the type under consideration are various food products, such as coffee and shortening. In merchandising such products it is desirable to provide instructions with regard to their use or recipes in which they are employed as ingredients, because in this way, the customer benefits from knowledge of the proper way to use the product and of the varied uses to which it may be put, while the fuller use of the product encouraged by such information results in increased sales to the advantage of the producer.

However, with containers of the type under consideration, it is preferable to secure the opening tool to the top cover of the can so that it is clearly visible when the customer wishes to open the can. Consequently, the opening tool pre-empts the portion of the can that is most noticeable and hence advantageous as a location for instructions or recipes as mentioned above. Further, the opening tool usually lies upon and projects above the surface of the cover and thus has heretofore rendered it impractical to apply an informative label in the desired position on the cover without detracting from the appearance of the can since the label would not ordinarily lie smoothly on the cover. Moreover, since the tool is usually secured to the can top so that it lies on and projects from the surface thereof, it presents an appearance that is not altogether pleasing. It has been impractical to attempt to improve the appearance of the can by merely affixing a label to the top cover over the opening tool, for to do so resulted in undesirably concealing the opening tool and is otherwise impractical as mentioned above.

One object of the present invention is to provide a label that may be applied to such a can top without concealing the opening tool.

A second object is to provide a label that may be smoothly applied to a can top despite the fact that the latter has an opening tool secured to and projecting from its surface.

A third object is to provide a can top label that is securely retained in place.

Another object is to provide a label that may be easily and quickly applied to the can top.

A further object is to provide a can top label that may be removed for preservation without tearing or otherwise impairing it.

Other objects and advantages of the invention will become apparent upon consideration of the following detailed description of illustrative embodiments of the invention when read in conjunction with the appended claims and the accompanying drawings.

In carrying out the invention, to obviate the aforementioned disadvantages, there are provided several different forms of labels, all of which are characterized by being formed with a cut-out or opening adapted to be fitted over the opening tool to position the label on the cover. All of the different forms of labels are characterized also by being securely retained on the can cover, and further, in leaving the opening tool clearly visible, although in most instances the label is retained in place by the tool.

Figure 1 is a perspective view of a conventional type of can having an opening device removably secured to the top cover;

Figure 2 is a plan view of the can top with a label positioned thereon that is provided with a cutaway conforming to the shape of the opening tool to fit the label thereover, the label being turned relatively to the tool and retained thereby;

Figure 3 shows a label somewhat similar to that of Figure 2 but which is retained on the can cover by frictional engagement of its periphery with a flange on the cover;

Figure 4 is a sectional view taken along the line 3—3 in Figure 3.

All of the remaining figures are plan views of can tops showing various forms of labels positioned thereon.

Figures 5, 6 and 7 show labels having P-shaped, spear-shaped and T-shaped openings, respectively, adapted to be fitted over the opening tool;

Figures 8, 9 and 10 illustrate labels having openings similar to but smaller than those of the labels shown in Figures 5, 6 and 7, respectively;

Figure 11 illustrates another position for the label shown in Figure 10;

Figures 12 and 13 show labels having slots or notches cut away at their edges to fit the labels over the opening tool; and

Figures 14 and 15 illustrate labels having openings adapted to be fitted over the opening tool and positioned about the end of the shank thereof.

Referring to the drawings, the numeral 10 in

Figure 1 designates a can of conventional type that is closed by a flanged top cover 11 and which is opened to afford access to its contents on tearing away a sealing strip 12 by applying an opening tool 13 thereto. The opening tool 13 is of the familiar wire key type having a shank 14 and a head or handle portion 15, extending angularly from one end of the shank. The opening tool 13 is usually mounted centrally of the cover 10 within the peripheral flange 16 thereof and below the top edge of the latter. In the usual practice, the tool is removably secured to the cover by soldering, riveting, welding or otherwise detachably fastening the tool at one point thereof, as for example a flattened portion 17 at the end of the shank 14.

As mentioned above, the presence of the tool 13 on the top cover 11 has heretofore produced an unfinished appearance and has resulted in introducing difficulties to the satisfactory application of a label to this portion of the can, although the latter is an obviously desirable location for the presentation of advertising or instructive information.

The labels of the invention are preferably made of stiff, light cardboard and in the embodiments illustrated are circular in outline to correspond with the contour of the cover 11.

The label 20 illustrated in Figure 2 has a cut-out or opening 21 that is slightly larger than but corresponds substantially to the shape of the head and shank of tool 13 so that the opening may be fitted over the tool for positioning the label in close contact with the surface of the cover 30 within the flange of the latter. In this form the end of the portion of opening 21 that fits over the shank 14 of the key is widened to form a substantially triangular slot 22 so that when positioned on the cover the label may be turned 35 relatively to the tool for engaging imperforate portions of the label beneath the head 15 of the tool.

The label 23, illustrated in Figure 3, is similar to that shown in Figure 2 in that the opening 24 corresponds to the shape of the tool and is slightly larger than the latter for fitting the label over the tool. However, the label 23 not only corresponds in outline to the contour of the cover internally of flange 16, but also is of a size to fit 45 closely within the cover for frictionally engaging the flange 16 to be retained in place by the latter.

The label 25 of Figure 5 has a P-shaped opening comprising a slot 26 slightly longer than the tool and wider than the shank thereof. At one 55 end and side of the slot 26 a lateral extension 27 is formed providing a secondary opening slightly larger than approximately one-half the head of the tool. The label is fitted over the tool 13 by movement along the cover toward the major axis 60 of the tool to engage the imperforate portion 28 of the label opposite extension 27 beneath one side of the head 15 of the tool, with the corresponding edge of slot 26 against the adjacent side of the tool. When released the label fits flatly 65 against the cover as the enlargement 27 and slot 26 fall into place over the other side of the head 15 and the shank 14 of the tool.

The label 30 of Figure 7 has a roughly T-shaped opening comprising a slot 31 slightly wider 70 than the shank of the tool but not quite so long as the latter and formed at one end with lateral extensions 32 at each side providing a secondary opening smaller than the head of the tool. When the secondary opening, or cross-bar of the T, is fitted over the head 15 of the tool by being drawn

downwardly thereover, the slot 31 falls about the shank 14 of the tool and the label lies flat against the cover with an imperforate portion 33 above the extensions 32 engaged beneath the head of the tool.

The label 34 of Figure 6 has a spear-shaped opening comprising a slot 35 slightly wider than the shank of the tool with a triangular extension 36 the sides of which are slightly longer than the width of the head 15 of the tool. The label 34 is fitted over the tool by drawing the triangular extension 36 downwardly over the head 15 of the tool to position part of the extension 36 beneath the head 15 and engage adjacent imperforate portions 37 beneath the head of the tool. When 15 the label is released it fits flatly against the cover as slot 35 falls into place over the shank 14 of the tool.

The labels 40, 41 and 42 of Figures 8 to 10 are similar to the labels 25, 34 and 30 illustrated in Figures 5 to 7 respectively, except that the slot portions 43, 44 and 45 of the openings thereof are shorter than the tool 13 or shank thereof. Consequently, when fitted over the tool an imperforate portion of each of these labels, located 25 beyond the lower end of the short slot, engages over part of the shank 14 of the tool. As a result, these labels, although retained in place by the head 15 of the tool, do not lie flat against the can cover as in the other forms of label. However, after the enlarged parts of the apertures are fitted over the head of the tool, these labels may be turned through 180° while advancing the apertures along the tool shank so that the labels will lie flat against the cover and be held in place 30 by the head and part of the shank of the tool, as indicated in Figure 11.

All of the various labels shown in the drawings may be very easily and quickly fitted over the tool and positioned in retained relation on the can 40 cover. The labels illustrated in Figures 5 to 11 are particularly easy to mount on the can top because of their application in a direction toward the major axis or toward the head of the tool, if desired, these labels may be bent slightly along 45 the lines A—A to facilitate the operation.

The labels illustrated in Figures 12 to 15 differ from those illustrated in Figures 2 to 11 as described above in that the cut-outs or openings therein which are adapted to be fitted about the 50 tool are all considerably smaller than the latter and do not approximate its shape.

The label 50 of Figure 12 is formed with a narrow slot 51 extending inwardly from its edge with the sides of the slot parallel to the median 55 line of the label. Slot 51 may be cut radially or non-radially of the label, depending upon whether the tool is secured centrally of the cover or at one side of the center.

The label 50 may be easily and quickly mounted 60 on the cover by slipping it beneath the unsecured head of the tool so that the slot 51 may be passed along the shank 14 until its upper end is positioned about the end 17 of the tool where it is secured to the cover. The label 50 is then retained in place flat against the cover by the head 65 15 and shank 14 of the tool.

The label 55 of Figure 13 has a slot 56 extending inwardly from the edge of the label at an angle to the median line of the latter. The label 70 is slipped beneath the tool to advance the slot 56 along the shank 14 until its inner end is positioned about the cover-attached portion 17 of the tool. Then the label is turned or twisted to position it fully within the cover, where it is re- 75

tained by engagement beneath the head and shank of the tool.

5 The label 60 of Figure 15 is formed with a narrow slot 61 of sufficient length to slip over the head 15 of the tool so that by twisting the label the slot 61 may be advanced along the shank of the tool, as indicated by the dotted lines, until the lower end of the slot is positioned about the 10 cover-attached portion 17 of the tool and im- 10 perforate portions of the label engaged beneath the head and part of the shank of the tool.

10 The label 62, illustrated in Figure 14, is formed with an oval opening 65 of sufficient size to fit over the head of the tool to be advanced along the shank thereof for positioning it about the 15 cover-secured portion 17 of the tool with the label retained by the head and shank of the latter. The label 62 may be slightly bent along the line B—B, to facilitate the mounting thereof. 20 Openings of other shapes, such as circular or triangular openings may be employed.

25 If desired, the various labels described above (except those of Figures 8 to 10 when mounted as illustrated) may be positioned on the cover prior to attachment of the tool, the end of the tool being then positioned in the label aperture and fastened in place, the labels shown in Figures 12 to 15 being particularly adapted to this manner of application and attachment.

30 The cut-outs or openings of the various labels illustrated in the drawings are preferably located centrally of the labels, or along the median line thereof, as this location corresponds to the usual location of the opening tool on the cover and 35 permits the informative or advertising matter to be symmetrically disposed on the labels. However, in cases where the tool is not secured to the cover centrally thereof, the opening in a label that passes over the tool will be correspondingly 40 located so that the label fits easily and neatly within the flanges of the cover and, preferably, is positioned centrally thereof. Small openings of 45 the types shown in Figures 11, 14 and 15 have certain advantages which especially commend their use. In distributing these goods it is possible for dust and even insects to accumulate under the label if the openings are unnecessarily large. Such an unsightly condition may be avoided by 50 making the openings in the label as small as possible.

55 If desired, all of the different labels illustrated, in addition to the label of Figure 3, may be of a size to fit closely within the cover so that their peripheries frictionally engage the flange of the cover to be retained thereby as well as by engagement of imperforate portions of the labels with the opening tool.

60 It will be noted that the invention provides labels which may be readily applied to the can top and lie smoothly thereon, which are securely retained in place, and which do not conceal the opening tool.

65 The labels of the present invention may bear advertising messages or recipes which vary from time to time in accordance with market conditions or the seasonal uses of the product. It should also be noted that all of the various labels may be easily removed without tearing them by slipping them over the opening tool before the 70 latter is detached to open the can, and when the tool is detached first the labels fall out upon tilting of the can and attract the attention of the consumer.

75 When the labels bear recipes they may be preserved for future reference by filing them

on a hook by means of the openings that fit the labels over the opening tool, or in the forms illustrated in Figures 12 and 13 by other openings 70 specially provided for this purpose.

It is to be understood that the term "label" as used herein includes multi-sheet advertising or recipe booklets and other analogous devices such as coupons to be used to obtain premiums, in special contests, or to obtain additional advertising or instructive literature. One or more of the 10 sheets in such a multi-sheet type may be perforated in the manner disclosed to obtain attachment. Such multi-sheets may be folded continuous sheets or may be bound together.

15 Although the labels have been shown as circular, it is apparent that labels having other outlines may be employed. The circular form of label or booklet is considered advantageous since its unusual shape attracts attention and hence the matter thereon is more apt to be read. However, 20 in order to present a pleasing appearance, it is deemed preferable to provide labels having outlines corresponding to the shape of the can cover.

25 It is to be understood that the various forms of labels disclosed herein are merely illustrative 25 embodiments of the invention and should not be considered as limiting the latter. Many changes and variations may be made without departing from the invention, and it is desired and intended to include all such changes and variations within 30 the scope of the appended claims.

I claim:

1. In combination with a container closed by a cover having an upstanding marginal flange and an opening tool removably secured to the cover 35 and adapted to be utilized to open the container; a flat label conforming to the shape of the cover positioned within the marginal flange and held in place thereon by engagement of a portion of the label beneath said tool, said label being formed 40 with an opening capable of being passed over said tool to remove the label from the cover.

2. In combination with a container having a side wall, and end having an upstanding marginal flange and an opening tool removably secured to 45 said end and adapted to be utilized to open the container; a flat label conforming to the shape of the cover positioned within the marginal flange and formed with an opening fitted over said tool with an imperforate portion of the label engaged 50 beneath the tool for retaining the label in place on said end.

3. In combination with a container closed by a cover having a peripheral flange; an opening tool having a shank removably secured adjacent 55 one end thereof to the cover; and a flat label having an outline substantially conforming to the shape of the cover and formed with an opening positioned about the shank of said tool adjacent its point of attachment to said cover and having 60 an imperforate portion engaged beneath an unsecured portion of said tool to securely mount the label on said cover within said flange.

4. In combination with a container closed by a peripherally flanged cover; an opening tool removably secured to said cover and adapted to be utilized to open the container; and a label having an outline conforming to the contour of said cover interiorly of its flange and formed with an opening adapted to be passed over said tool for 70 mounting the label on said cover with the peripheral edge of said label in engagement with the flange of said cover and an imperforate portion of the label engaged beneath said tool to retain the label on said cover.

5. In combination with a container closed by a cover; an opening tool removably secured to the cover at one part thereof and having a shank and a head portion extending from the shank adjacent one end thereof; and a label formed with an opening adapted to be fitted over said tool for positioning the label on said cover, said opening comprising a slot fitting about at least a portion of the shank of the tool and having at one end thereof an enlarged extension positioned in part beneath the head of said tool with an adjacent imperforate portion of the label engaged beneath said head to retain the label on the cover.

10 6. In combination with a container closed by a cover; an opening tool removably secured to the cover at one part thereof and having a shank and head portions extending from each side of the shank adjacent one end thereof; and a label formed with an opening adapted to be fitted over said tool for positioning the label on said cover, said opening comprising a slot fitting about the shank of the tool and having at one side at least of one end thereof a lateral extension forming an opening disposed beneath part of the head of said tool with an imperforate portion of said label adjacent said extension engaged beneath another part of said head to retain the label on said cover.

15 7. In combination with a container closed by a cover; an opening tool removably secured to the cover at one part thereof and having a shank and head portions extending from each side of the shank adjacent one end thereof; and a label formed with an opening adapted to be fitted over said tool for positioning the label on said cover, said opening comprising a slot fitting about the shank of the tool and having at each side of one end thereof a lateral extension forming an opening disposed beneath the head of said tool with an imperforate portion of the label at each side of said end of said slot engaged beneath the head of said tool to retain the label on said cover.

20 8. In combination with a container closed by a cover; an opening tool removably secured to the cover at one point thereof and having a shank and head or handle portions extending from the shank adjacent one end thereof; and a label formed with an opening adapted to be fitted over said tool for positioning the label on said cover, said opening comprising a slot of slightly greater width than the shank of said tool and fitting about the latter, said slot having at one end thereof an enlargement smaller than the head of said tool and partly positioned beneath the latter with

an adjacent imperforate portion of the label engaged beneath the head of said tool to retain the label on the cover.

25 9. In combination with a container closed by a flanged cover; an opening tool removably secured to the cover centrally thereof and having a shank and a head portion extending from the shank adjacent one end thereof; and a label having an outline conforming to the contour of said cover within the flange thereof and formed with an opening adapted to be fitted over said tool for positioning the label on the cover, said opening comprising a slot of slightly greater length than said tool and of slightly greater width than the shank thereof with one edge of said slot disposed closely adjacent the median line of the label, said slot fitting about the shank of the tool and having at one end thereof a lateral extension positioned in part beneath the head of said tool with an adjacent imperforate portion of the label engaged beneath said head to retain the label on the cover.

30 10. In combination with a container closed by a cover having an upstanding peripheral flange; an opening tool removably secured to the cover at one part thereof; and a flat label conforming to the shape of the cover having an opening adapted to be fitted over said tool on movement of the label on the cover along the major axis of said tool to position the label within said flange with an imperforate portion of the label engaged beneath an unsecured portion of said tool to retain the label on the cover.

35 11. In combination with a container closed by a cover; an opening tool removably secured at one part thereof to the cover and adapted to be utilized to open the container; and a label having a portion cut away from its edge towards the center thereof for fitting the label over an unsecured portion of said tool and positioning it on said cover with an imperforate portion thereof engaged beneath an unsecured portion of said tool to retain the label on the cover.

40 12. In combination with a container closed by a cover; an opening tool removably secured at one part thereof to the cover and adapted to be utilized to open the container; and a label formed with a slot extending inwardly from its edge and having the sides of said slot disposed parallel to the median line of the label for fitting it about an unsecured portion of said tool to position it on said cover with an imperforate portion of the label engaged by said tool to retain the label on said cover.

45 GEORGE I. CHATFIELD.
